Inventor:

Milton Tibbets.

UNITED STATES PATENT OFFICE.

MILTON TIBBETTS, OF DETROIT, MICHIGAN, ASSIGNOR, BY MESNE ASSIGNMENTS, TO
THE ISKO COMPANY, OF CHICAGO, ILLINOIS, A CORPORATION OF DELAWARE.

REFRIGERATING APPARATUS.

1,296,879.

Specification of Letters Patent. Patented Mar. 11, 1919.

Application filed September 8, 1916. Serial No. 119,045.

To all whom it may concern:

Be it known that I, MILTON TIBBETTS, a citizen of the United States, and resident of Detroit, Wayne county, State of Michigan, have invented certain new and useful Improvements in Refrigerating Apparatus, of which the following is a specification.

This invention relates to refrigerating apparatus, and particularly to apparatus of the compression type.

It is one of the objects of the present invention to provide a compression type apparatus that will be adapted to domestic use, that is, with a domestic refrigerator box of the size and form now generally in use.

Another object of the invention is to provide a compressor and a blower and means for intermittently operating them, thus permitting the use of a smaller motor than would be possible if both compressor and motor were operated together.

Other objects of the invention will appear from the following description taken with the drawings which form a part of this specification, and in which:

Figure 1 is a front elevation and part vertical sectional view of a refrigerating apparatus embodying this invention;

Fig. 2 is an end view of the upper part of the apparatus shown in Fig. 1, parts being broken away to show the condenser coil; and

Fig. 3 is a detail view of the intermittent connection.

Referring to the drawings, 10 represents a refrigerator box of usual construction having food compartments 11 and a refrigerating compartment 12. In the latter compartment a refrigerating or expanding chamber or coil 13 is arranged and it is connected through a suitable pipe 14 and expansion valve 15 with a condenser 16 shown in the form of coils and arranged at the side of the refrigerator box. A compressor 17 is mounted on top of the box and is connected to the coil 13 and condenser 16 through pipes 18 and 19 respectively.

The apparatus shown is intended particularly for use with a refrigerant of low boiling point such as sulfur dioxide (SO_2), which permits of air cooling the condenser as shown. The refrigerant is compressed into the condenser, cooled therein, then expanded into the chamber 13 where it absorbs the heat in the refrigerator box, and

is drawn from there into the compressor to continue the circulating process.

To assist in promoting a circulation of cooling medium such as air about the condenser 16, a casing 20 is provided, having an inlet opening 21 at the bottom of the box where the air is coolest and an outlet 22 at the top connecting with a blower 23 shown as of the well known cirrocco type. The outlet opening of the blower is preferably directed upwardly as at 24.

Means are provided for operating the compressor and blower, shown in the form of a small electric motor 25. Separate driving connections in the form of parallel friction belts 26 and 27 are arranged for driving the compressor and blower from the motor. The belt 26 runs over pulleys 28 and 29 and the belt 27 over pulleys 30 and 31. If a sufficiently large motor is employed the compressor and blower may be driven simultaneously, but as the compressor is usually provided with a rather tight stuffing box making it difficult to start, means are provided for connecting the compressor and blower to the motor at different times or alternately, so that the load of only one of them will be on the motor at a time. One form of such means contemplates mounting the pulleys 28 and 30 loosely on the shaft 32 which is an extension of the armature shaft of the motor, and alternately connecting them to the shaft as by a sliding clutch sleeve 33 keyed on the shaft 32. Coöperating teeth 34 are provided on the sleeve and pulleys, and the sleeve is moved from one clutching position to another by a sliding rod 35 having an arm 36 forked in a groove 37 in the sleeve and having a lug 38 through which passes a link 39 pivoted eccentrically to a gear 40 driven by the shaft 32 through reducing gears 41, 42 and 43, the latter two being worm gears. Spaced nuts 44 on the link 39 are adapted to abut against the lug 38 near the ends of the stroke of said link for the purpose of shifting the rod 35 lengthwise as will be understood from the drawings, Fig. 2. In said figure, the pulley 28 is engaged by the clutch sleeve and the compressor is being operated while the pulley 30 is idle and the blower is still. When the gear 40 has made a half revolution the left hand unit 44 will have moved the rod 35 to the right so that the clutch will disconnect the pulley 28 and connect the pulley 30 thus

stopping the compressor and starting the blower. The next half revolution of the gear 40 will reverse the operation.

It will be understood that while but one form of the invention has been shown, other forms may be made without departing from the spirit or scope of the invention.

Having thus described my invention, what I claim and desire to secure by Letters Patent is:—

1. In a refrigerating apparatus, in combination, a condenser, a pump for circulating the refrigerant through the condenser, means to cause a circulation of air around said condenser, a motor and alternating driving connections from said motor to said pump and means.
2. In a refrigerating apparatus, in combination, a condenser, a pump for circulating the refrigerant through the condenser, means to cause a circulation of air around said condenser, and means to alternately operate said pump and said means.
3. In a refrigerating apparatus, in combination, a condenser, a pump for circulating the refrigerant through the condenser, means to cause a circulation of air around said condenser, and means comprising friction driving devices to alternately operate said pump and said means.
4. In a refrigerating apparatus, in combination, a condenser, a casing around the condenser, a pump for circulating the refrigerant through the condenser, a blower for circulating air through the casing, and means for operating the pump and blower.
5. In a refrigerating apparatus, in combination, a condenser, a casing around the condenser, a pump for circulating the refrigerant through the condenser, a blower for circulating air through the casing, and means for intermittently operating the pump and blower.
6. In a refrigerating apparatus, in combination, a condenser, a casing around the condenser, a pump for circulating the refrigerant through the condenser, a blower for circulating air through the casing, and means for alternately operating the pump and blower.
7. In a refrigerating apparatus, in combination, a condenser, a casing around the condenser, and means for intermittently circulating air through the casing.
8. In a refrigerating apparatus, in combination, a condenser, means for circulating the refrigerant therethrough, and means for intermittently circulating air around the condenser.
9. In a refrigerating apparatus, in combination, a condenser, means for circulating the refrigerant therethrough, and means operating independently of the refrigerant circulating means for circulating air around the condenser.

10. In a refrigerating apparatus, in combination, a condenser, means for circulating the refrigerant therethrough, and means operating independently of the refrigerant circulating means for intermittently circulating air through the condenser. 70

11. In a refrigerating apparatus, in combination, a condenser, means for circulating the refrigerant therethrough, and means operating alternately with the refrigerant circulating means for circulating air around the condenser. 75

12. In a refrigerating apparatus, in combination, a condenser, an expansion chamber, a connection between said condenser and said chamber including an expansion valve, a pump for circulating a refrigerant through said condenser and chamber, a motor for driving said pump, and means, operated when the pump is idle, for circulating air around said condenser. 80 85

13. In a refrigerating apparatus, in combination, a condenser, an expansion chamber, a connection between said condenser and said chamber including an expansion valve, a pump for circulating a refrigerant through said condenser and chamber, a motor for driving said pump, and means operated when the pump is idle, for circulating a cooling medium around said condenser. 90 95

14. In a refrigerating apparatus, in combination, a condenser, an expansion chamber, a connection between said condenser and said chamber including an expansion valve, a pump for circulating a refrigerant through said condenser and chamber, a motor for driving said pump, a blower for circulating air about said condenser and means for driving the blower when the pump is idle. 100

15. In a refrigerating apparatus, in combination, a condenser, an expansion chamber, a connection between said condenser and said chamber including an expansion valve, a pump for circulating a refrigerant through said condenser and chamber, a motor for intermittently driving said pump, a blower for circulating air about said condenser, and means for driving the blower from the motor when the pump is idle. 105 110

16. In a refrigerating apparatus, the combination with a compressor and a fan, of a motor, and means alternately connecting the compressor and fan to the motor. 115

17. In a refrigerating apparatus, the combination with a compressor and a fan, of a motor, and means driven by the motor alternately connecting the compressor and fan to the motor. 120

18. In a refrigerating apparatus, the combination with a compressor and a fan, of a motor, and separate friction driving connections from the motor to the compressor and fan. 125

19. In a refrigerating apparatus, the combination with a compressor and a fan, of 130

a motor, independent driving connections from the motor to the compressor and fan, and means for alternately operating said connections by the motor.

5 20. In a refrigerating apparatus, in combination, a refrigerating box, a refrigerating coil therein, a condenser connected to said coil and mounted at the side of the box, a casing over said condenser, a compressor 10 connected to said condenser and coil and mounted on top of the box, a blower connected to said casing and mounted on top of said box, and a motor for operating said compressor and blower.

21. In a refrigerating apparatus, in combination, a refrigerating box, a refrigerating coil therein, a condenser connected to said coil and mounted at the side of the box, a casing over said condenser, a compressor connected to said condenser and coil 20 and mounted on top of the box, a blower connected to said casing and mounted on top of said box, and a motor for alternately operating said compressor and blower.

In testimony whereof, I affix my signature.

MILTON TIBBETTS.
